UNITED STATES PATENT OFFICE.

JIRAH R. WINSOR, OF PERRY, IOWA, ASSIGNOR OF ONE-HALF HIS RIGHT
TO ORA WINSOR, OF SAME PLACE.

IMPROVEMENT IN LOCKS.

Specification forming part of Letters Patent No. **218,805**, dated August 19, 1879; application filed
June 7, 1879.

To all whom it may concern:

Be it known that I, JIRAH R. WINSOR, of Perry, in the county of Dallas and State of Iowa, have invented certain new and useful Improvements in Locks; and I do hereby declare that the following is a full, clear, and exact description of the construction and operation of the same, reference being had to the annexed drawings, making a part of this specification, and to the letters and figures of reference marked thereon.

Figure 1 of the drawings is a representation of an interior of my lock. Fig. 2 is a longitudinal sectional view; and Fig. 3 is a view of the key.

Identical parts in the drawings are designated and referred to by the same letters.

My invention relates to locks; and it consists in the improvements in the construction of the same hereinafter fully described, and particularly pointed out in the claims.

A represents the lock-bolt, which is provided with the head a , which enters the retaining-plate on the door-casing, and the spring a^1 , which engages the standard a^2 of the case of the lock and keeps the body of the bolt pressed against the stem a^3 of the case, or against the key when the bolt is being operated by it. It is also provided with a lug, a^4 , to engage the spring B, which is held in operative position by the standard b . A' is a flange attached to the inner end of the bolt, which is of the same width as the head a , and preserves the proper position of the bolt by contact with the case-plates C and C' upon its inner and outer sides. C is the rear plate of the lock-case, and C' is the removable plate of the same.

The lock-bolt A is also provided with the transverse bolt D, which works freely in a suitable opening in the body of the bolt A. This bolt D is provided with the plate d and the projecting head d^1 , and the spring d^2 forces the head d^1 against the case in a manner that will cause it to enter the opening d^3 in the plate C, if not otherwise prevented.

D' is the recess in the body of the bolt A, in which the key works to operate this bolt. The plate d of the bolt D extends over this recess. The key to operate this lock is con-

structed with the step e of the web E, and a step, e^1 , of the same. These steps are so constructed that, as the key is operating the bolt in either direction, the step e will raise and carry the bolt D by contact with the plate d . The step e^1 , by bearing upon the plate C—or C', owing to which side the key has been inserted from—holds the key in proper position to thus carry the bolt D over the opening d^3 , and permit the bolt A to be operated.

In case a false key, or a key not having the points e e^1 , is inserted, the spring d^2 will force the bolt D into the opening d^3 of the case and arrest the key and the movement of the bolt, before the bolt has been withdrawn from the retaining-plate of the door-casing. By this means the movement of the bolt will be permanently arrested. This bolt A is also provided with the openings a^5 and a^6 , which are connected by the passage a^7 .

The bolt A is thrown out by the key to the position indicated by the full lines. When the key is removed the spring B withdraws the bolt, so as to cause the stem a^3 to enter the recess formed in the opening a^5 by the flange a^8 . This stem a^3 thus securely holds the bolt A in a locked or outward position.

To disengage the stem a^3 from this recess, the properly-fitted key will first engage the incline e^2 of the notch D' and carry the bolt outward sufficiently to relieve the flange a^8 from the stem a^3 , when the key will raise the inward end of the bolt A and withdraw it from the retaining-plate of the door, passing the stem into the recess a^6 . The spring a^1 returns the bolt to its horizontal position upon the withdrawal of the key.

The operation of the lock is as follows: The bolt A being in an outward position, the key, upon being inserted and force applied to its bow, first engages the incline e^2 , and by passing the bolt outward releases the stem a^3 from the flange a^8 . The key then raises the plate d and bolt D, and carries the same in an upward position and over the opening d^3 in the case. In the meantime the stem a^3 is transferred from the recess a^5 through the passage a^7 into the recess a^6 . In locking, the key first raises the bolt A and passes it forward, the recess a^6 being again in contact with the stem a^3 .

The knob-stem F is provided with the annular groove f, which receives and retains the arm f¹ of the shaft F'. This annular groove is to permit the knob to be turned after the manner of the common knob without operating the latch or injury to the same. f² is a spring attached to the shaft F', to return the arm f¹ and the latch f³ to the position indicated in the drawings. f³ is the latch, which, as the door is closed, engages the catch on the door-casing, and is turned up as shown in dotted lines. Upon entering the catch the latch returns to position indicated in the drawings by the action of the spring f².

To open the door the knob is either pulled or pushed as required, which places the latch in nearly a horizontal position, when it will freely pass from the catch and be returned to position shown by the action of the spring f².

Having thus described my invention, what I claim as new, and desire to secure by Letters Patent, is—

1. In a lock, the bolt A, provided with the recesses a⁵ a⁶ and connecting-passage a⁷, and the flange a⁸, in combination with the springs a² and B, as and for the purposes substantially as set forth.

2. In a lock, the bolt A, provided with the spring a² and a suitable opening for the bolt D, in combination with the bolt D, provided with the plate d and head d¹, and the case C, provided with the opening d³, as and for the purposes substantially as set forth.

3. The key provided with the steps e e¹, in combination with the plate d, spring d², and bolt D, bolt A, and opening d³ in plate C, as and for the purposes substantially as set forth.

In testimony that I claim the above I have hereunto subscribed my name in the presence of two witnesses.

J. R. WINSOR.
